MAXWELL S. HART, OF NEW BRITAIN, AND MAURICE G. STEELE, OF FARMINGTON, CONNECTICUT, ASSIGNORS TO THE HART & HUTCHINSON COMPANY, OF NEW BRITAIN, CONNECTICUT, A CORPORATION OF CONNECTICUT

RADIATOR

Application filed January 3, 1928. Serial No. 244,191.

The invention relates to heating apparatus for buildings, and more particularly to an improved form of radiator and radiator enclosure adapted to be located below the floor of a room.

One object of this invention is to provide a heating apparatus of the above nature employing a radiator of the fin type and provided with means for supplying the radiator with air to be heated, either from the floor of the room or from an outside source.

A further object is to provide a heating apparatus of the above nature having a casing located below the floor of the room, said casing including an upper angular frame having wall and floor grilles for permitting the passage of air therethrough.

A further object is to provide an improved form of damper mechanism, adapted to be manipulated from the floor of the room, for shutting off the floor grille and opening communication with an outside source of cold fresh air.

A further object is to provide a device of this nature which will be simple in construction, inexpensive to manufacture, easy to install and manipulate, compact, ornamental in appearance, and very efficient and durable in use.

With these and other objects in view there has been illustrated on the accompanying drawings one form in which the invention may be conveniently embodied in practice.

Fig. 1 represents a front view of the radiator.

Fig. 2 is a side view of the same shown partly in section.

Fig. 3 is a sectional view on a somewhat smaller scale of the heating apparatus showing the arrangement of the radiator within the casing below the floor of a room.

Fig. 4 is a perspective view of the angular grille member.

Referring now to the drawings in which like reference numerals denote corresponding parts throughout the several views, the radiator unit comprises a pair of upper and lower elongated rectangular headers 10 and 11 connected by a plurality of vertical tubes 12, seven in number in this instance. The

tubes 12 are arranged in two parallel rows in staggered relation and have their extremities threaded for engaging in threaded apertures in the headers 10 and 11. The tubes 12 are held in place by means of nuts 13 which are 55 screwed up against said headers. The tubes are provided with a plurality of parallel inclined fins 14, soldered or otherwise secured thereto, said fins being adapted to provide a high rate of heat transfer from the radiator 60 unit to the air passing through it.

In order to supply heat to the radiator, provision is made of a steam or hot water inlet pipe 16 connected to the top header 10, and the spent heating fluid is adapted to be 65 conducted away through an outlet pipe 15 connected to the bottom header 11. Provision is also made of a standard radiator air valve 17 located in the top header 10, for allowing air to escape, but preventing loss of 70 steam or hot water.

The radiator unit just described is located in a recess 18 formed within a wall 18a of the building just below the floor of the room, and said radiator unit is adapted to be supported on a shelf 19 extending rearwardly from a vertical casing section 19a which is in alignment with the inner surface of said wall 18a. 75

In order to form a passageway 20 for conducting cold air from the floor of the room, provision is made of a forward vertical casing section 21 which is arranged parallel to the vertical casing section 19a, whereby air will be drawn down through the floor of the room and caused to pass under the shelf 85 19 and be delivered through a damper opening 22 to a point below and behind the radiator unit.

The air inlet passage 20, the radiator recess 18, and the stack 22a are closed by an angular member 22b consisting of an integral floor grille 23, having openings 23a for permitting cold air to be drawn down through the floor, and a wall grille 24 having openings 24a through which the air heated by the 90 radiator is adapted to enter the room. 95

A "fresh air" grille 25 is also provided for permitting cold air to be drawn from out of doors, through a passage 26 connecting with the radiator recess 18. In order to permit 100

the air inlet from the floor grille 23 to be closed, and the outside air inlet through the passage 26 to be opened, provision is made of a damper 27 hinged in the wall 18a at a point adjacent said passage 26. The damper 27 is adapted to be manipulated by means of a damper-control rod 28 which extends up through the floor grille member 23, said damper-control rod being connected at its lower end to one arm of a bell-crank lever 29 fulcrumed at 30 to the supporting shelf 19. The other arm of the bell-crank lever 29 is connected by a link 31 to a rod 32 connected to said damper 27, the motion of the damper 27 being further guided by a rod 33 pivoted in the bottom corner of the inlet passage 20 and connected to the joint between the link 31 and the rod 32. The damper-control rod 28 is preferably mounted frictionally in the floor grille 23 so that the damper 27 may be maintained in either of its extreme positions or in any intermediate position, according as to whether it is desired to deliver to the radiator cold air from the bottom of the room being heated, outside air, or a mixture of both.

For the purpose of shutting off the flow of warm air from the radiator through the stack 22a and into the room, a handle-operated damper 34 is provided, said damper 34 being controlled by a handle 35, extending through a slot 36 in the wall grille member 24.

In operation, assuming that the damper rod 28 has been pushed way down as far as it will go so that the damper 27 is closed, cold air from the floor of the room will pass down through the floor grille openings 23a, the passage 20, up through the damper opening 22, into the radiator recess 18, through the radiator fins 14, up through the stack 22a, and out through the wall grille 24 into the room again. When it is desired to deliver fresh outside air to the radiator, the operator will pull the damper rod 28 up as far as it will go, thus causing the damper 27 to close the opening 22 and open the passage 26. When the damper rod 28 is adjusted in any intermediate position, the air supplied to the radiator will be a mixture of room air and outside air, the relative proportions of each depending on the position of the damper 27. The direction of the air flow is shown by the arrows in Fig. 3.

It will be understood that while the radiator unit is herein disclosed as located within a recess of a wall, the casing of said radiator may be located adjacent or away from said wall within the spirit and scope of said invention.

One advantage of the present invention is that the radiator occupies no space whatever in the room.

A further advantage is that it is not necessary to employ a grille at an elevated position on the wall of the room as was the case

with former so-called "concealed radiators."

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In an apparatus for heating a room, a radiator located below the floor of said room within a recess in the wall of the building, a damper for interchangeably supplying said radiator with cold air to be heated from the floor of said room or from an outside source and damper-controlling means extending up through the floor into an accessible position.

2. In an apparatus for heating a room, a radiator located below the floor of said room within a recess in the wall of the building, a damper for interchangeably supplying said radiator with cold air to be heated from the floor of said room, or from an outside source, or for supplying a mixture of both, and a controlling rod extending up through the floor and connected to said damper by a system of levers and links.

3. In an apparatus for heating a room, a chamber located at the junction of the wall and floor below the lever of the floor, means for supporting a radiator within said chamber, said chamber having a passage below said floor for conducting cold air from said room to said radiator, and an angular member closing the top of said chamber and having grille openings for allowing the passage of cold air down from the room to said radiator, and of hot air from said radiator into said room.

4. In an apparatus for heating a room, a chamber located at the junction of the wall and floor below the level of the floor, means for supporting a radiator within said chamber, said chamber having a passage below said floor for conducting cold air from said room to said radiator, and an angular member closing the top of said chamber, said angular member having a horizontal grille provided with openings to permit the passage of cold air from the room to said radiator.

5. In an apparatus for heating a room, a chamber located at the junction of the wall and floor of said room below the level of the floor, means for supporting a radiator within said chamber, said chamber having a passage below said floor for conducting cold air from said room to said radiator, and a one-piece integral plate member closing the

top of said chamber and having grille openings for allowing the passage of cold air down from the room to said radiator, and of hot air from said radiator into said room.

5 In testimony whereof, we have affixed our signatures to this specification.

MAXWELL S. HART.
MAURICE G. STEELE.
